UNITED STATES PATENT OFFICE
2,566,301
PORTABLE REFRIGERATION BOX

Alan Albert, Denver, Colo.

Application June 13, 1946, Serial No. 676,372

1 Claim. (Cl. 62—92)

1
This invention relates to refrigeration apparatus and more particularly relates to portable or transportable refrigerating units.

In the past, small-capacity refrigerating units, such as the household mechanical refrigerator, or the like, have provided a sharp-freezing container and associated storage space where relatively low temperature atmospheres are maintained. Heat exchange surfaces, such as walls, tubing and the like are included as part of such structures and a gas-refrigerant is circulated through the tubing and in contact with heat-transfer surfaces and then is returned through a condenser-compressor circuit for repeated recirculation.

Such units are satisfactory where the storage unit is to be operated continuously in one location, but such a system is not suited for operating portable storage containers, such as those used by hunters and fishermen, for example. Containers are available for such usage, which have storage facilities for a quantity of ice or solid carbon dioxide, but these materials melt so rapidly that the containers function as effective refrigerators for short time intervals only unless the refrigerant supply is replenished.

It is an object of the present invention to provide a simple, economical and efficient refrigeration method which may be utilized in portable storage receptacles for protracted periods.

Another object of the invention is to provide simple, durable and efficient refrigerator apparatus which is easily transported and provides a substantial amount of storage space.

Other objects reside in novel combinations and arrangements of parts, all of which will be fully described in the course of the following description.

To afford a better understanding of the invention, reference will be made to the accompanying drawings illustrating typical embodiments. In the drawings, in the several views of which like parts have been designated similarly,

Fig. 1 is a vertical central section through a portable refrigerator unit embodying features of the present invention; and

Fig. 2 is an enlarged section through tank 9 showing conduit 13 extending from an elevated position in tank 9.

As illustrated in Fig. 1, the features of the present invention may be incorporated in a portable refrigerator unit of the type used by fishermen and for outing purposes. The refrigerator R comprises a double-walled body 3, preferably cylindrical and having a double-walled bottom 55 which vaporizes a portion of the liquid. This

2
4, and a double-walled lid 5 hinged at 6 to permit access to the interior storage compartment 7. The space between the inner and outer walls of body 3, bottom 4 and lid 5 is substantially filled with a suitable heat insulating material 8 to maintain compartment 7 in heat-insulated relation to the atmosphere. A refrigerant storage tank 9 is supported from body 3 and preferably has a filling opening 10 which normally is closed by a cap 12. A conduit 13 may extend from an elevated position in tank 9 through a bottom outlet therein as shown in Fig. 2 or may extend directly from the bottom outlet as shown in Fig. 1, and is wound as a coil assembly 13a in body 3 with an outlet extending through the body to the atmosphere, as shown at 14. Preferably, a valve 15 controls the discharge of refrigerant from tank 9 into conduit 13 and a second valve 16 at outlet 14 controls the rate of escape of evolved gases to the atmosphere.

A variety of refrigerants may be used in the operation of the refrigerator, but I prefer to use "Freon" (CCl₂F₂) or other fluorine-substituted hydrocarbons, such as CHFCl₂ because of their non-noxious qualities and liquid condition. However, solid carbon dioxide, sulfur dioxide or the like may be used if these other refrigerants are not available.

In use, the refrigerator R may be transported manually, or by vehicle, pack animal or the like to any location where it is desired to use the unit in the preservation of perishables or the like. As an example, fishermen frequently will go into remote sections to stay for protracted periods because of the good fishing conditions prevailing at such places. Usually, such locations are so far away from any market source of ice or solid carbon dioxide that it is not possible to preserve the catch under refrigerated conditions, even though it would be desirable to do so if possible.

At such a location, the unit R may be kept in an inactive condition until the actual refrigerating need arises, although preferably the reservoir R will be filled with a refrigerant such as "Freon" during transportation and an additional supply will be carried in suitable containers for use as the original reservoir supply is exhausted. The unit shown in Fig. 1 is activated by partially opening valve 15, whereupon the liquid in tank 9 is released into coils 13a where it evolves into a vapor due to expansion in the coils 13a. In order to activate the unit with a tank 9 as shown in Fig. 2, the valve 15 is partially opened, causing a release of pressure within the reservoir 9 which vaporizes a portion of the liquid. This

vapor rises above the liquid and enters conduit 13 to flow past valve 15 and thence into the coil circuit 13a, producing the heat transfer action in the coils which maintains a low temperature condition in compartment 7 and its contents.

Preferably the discharge to atmosphere of the evolved vapors is at a rate controlled by the setting of valve 16, and in this way, the delayed discharge serves to keep the desired refrigerating conditions within the container for protracted periods, as for example three or four days.

Preferably a sight gage or other level indicator is mounted on the exterior of tank 9 so that the operator may know when the liquid content of tank 9 has been dissipated. At such time, it will be advisable to refill the tank 9 through opening 10 to permit continuance of the refrigeration action. It will be apparent that by repetitions of the above procedure, a unit of this type may be kept in continuous operation for an indefinite period so long as a sufficient supply of the refrigerant is available.

By employing an insulated construction of the type disclosed, only a relatively small amount of gas flow is required in maintaining desired temperatures after the initial temperature reduction to prescribed limits has been effected. Also, if it is necessary to place the unit in locations where it may be exposed to sun, light or other heating factors, the double wall construction is effective in preventing any heating of the storage compartment from such external sources. The design may be varied substantially to suit capacity and other requirements, and as long as the circuit arrangement of the general type here-

inbefore described is provided, satisfactory results will be obtained.

What I claim and desire to secure by Letters Patent is:

5 In a refrigeration box for perishables, an outer shell, an inner shell spaced therein to provide an open space between said inner and outer shells, an insulation material in said open space, an insulated cover normally supported on the box and providing an access opening to the interior, a refrigerant storage tank mounted on said box, a circuitous conduit extending from said tank in heat-transfer relationship to the inner shell, means for controlling the release of refrigerant from the storage tank into said conduit, and means adjacent the end of said conduit for discharging evolved vapors to atmosphere.
